UNITED STATES PATENT OFFICE.

SAMUEL KAYE, OF COLUMBUS, MISSISSIPPI.

CAP-FINGER.

1,234,768.

Specification of Letters Patent. Patented July 31, 1917.

Application filed July 12, 1913. Serial No. 778,714.

To all whom it may concern:

Be it known that I, SAMUEL KAYE, a citizen of the United States, residing at Columbus, in the county of Lowndes and State of 5 Mississippi, have invented certain new and useful Improvements in Cap-Fingers, of which the following is a specification.

My invention relates to an improvement in bottle-capping machines, and more particularly to an improved cap-finger, the purpose of which is to receive and center the bottle-cap preparatory to its being thrust through the rubber throat into the conical throat of the capping-machine where it is 15 held frictionally at its edges by the walls of the throat preparatory to being secured to a bottle.

This invention consists in a finger adjustably supported in a suitable slide in connection with a sleeve and receiving cup, the two latter being slidably and concentrically sleeved upon the finger and located in position to be acted upon by a filling-head, which, when lowered with respect to the 25 finger, first has the effect of pressing the receiving cup downward against the action of a spring until the cup has moved a certain distance, when it causes a release of the sleeve from the cap-finger by permitting the 30 lock which holds the two together to drop partly to one side into a recess formed for it in the upper end of the receiving-cup. Thereupon the sleeve is permitted to move down upon the finger by gravity or otherwise 35 with the continued downward movement of the receiving-cup, thereby leaving the upper end of the finger protruding above the sleeve just as the throat of the filling-head has descended to receive the cap. This 40 is thrust into the throat where it is held by the frictional engagement of the outer edge of the cap with the tapering walls of the throat. Thus the finger virtually reduces in size just before or as the throat drops into 45 position to receive the cap, after which the filling-head is lifted with the cap in readiness to fill a bottle to be inserted through the mouth of the filling-head (in the place previously occupied by the finger) to be 50 filled and capped.

In the accompanying drawings:—

Figure 1 is a view in side elevation,

Figs. 2, 3, and 4 are sectional views at right angles to Fig. 1 on the line 1—1 of 55 that figure showing the parts in different positions they assume,

Fig. 5 is a horizontal section, and

Fig. 6 is a view in perspective of the cap-chute.

This invention coöperates with the filling-head set forth in application Serial No. 778,715 filed simultaneously with this application, in that its function is to guide and support the bottle-cap while the head receives the latter and frictionally holds 60 it preparatory to receiving the mouth of the bottle to be filled, ready to apply the same to the bottle on the completion of the filling operation, after which the filling-head is lifted and the bottle removed from 65 the machine.

The numeral 1 represents the cap-finger. This is provided with a screw-threaded lower end 2, which is adjustably held in the 75 slide 3, which latter fits and slides in correspondingly-shaped guide-grooves 4, 4, in the rotary table 5.

A sleeve 6 has two bores to fit the cap-finger upon which it is slidably mounted, the shoulder 7 between the bores operating as 80 a stop to prevent further movement of the sleeve in an upward direction upon the finger.

A receiving-cup 8 is slidably mounted on the sleeve. This is stopped in one direction 85 by the shoulder 9, whereas in the other direction it is limited by the ball-lock 10, which plays in and out through an opening 11 formed in the sleeve 6, the ball being of greater diameter than the thickness of the 90 sleeve at the opening 11 and is formed so that under normal conditions it rests partly in the notch 12 in the side of the finger and the elongated groove 13 in the wall of the cup, thus locking the finger and sleeve together, and permitting the cup to slide up 95 and down freely on the sleeve while precluding its turning axially.

The upper end of the groove 13 is enlarged to form a pocket 14, which receives 100 the ball-lock 10 when the receiving-cup shall have been depressed or forced down to the position shown in Fig. 4. This causes a release of the sleeve 6, permitting the latter to move down with the receiving-cup by 105 gravity or otherwise, away from and exposing the upper end of the finger 1, leaving the cap C resting upon the stripped upper end of the finger, the sleeve clearing the way, and the finger thus becoming reduced 110 in size so as to enter the throat T of the filling-head. This thereupon comes down

over the end of the finger and the cap, resulting in the edges of the cap being held frictionally against the wall of the throat, and the body of the cap brought against the rubber plug P in the throat, which latter insures seating the cap properly and forces the bottle free from the throat when the head lifts or rises from a bottle after it has been capped.

10 The caps are fed down through the chute 19, whence they are raked by the lugs 20, 20, on the upper end of the cup 8, as they pass through the slots 21, 21, in the travel of the finger with the rotation of the table 5. 15 One cap C is raked from the chute at a time, it being held centered upon the upper end of the finger 1, which normally protrudes just slightly above the upper end of the sleeve, which upper end of the sleeve is 20 normally slightly below the upper end of the cup, thus forming in effect an annular groove of which the upper edge of the sleeve forms the bottom wherein to receive the edge of the cap, all of which is shown in 25 Fig. 2.

The vertical bottle-guide 25 secured to the outer end of the slide 3 receives the bottle. The slide is reciprocated by a cam (not shown) through which the anti-friction 30 roller 26 travels.

The bottle-guide 25 is adjusted to the size of the bottle by the nut 27, of which there are two, only one, however, of which is shown in Fig. 1, just as the finger is raised 35 or lowered according to the height of the bottle by turning its threads 2 in the slide 4.

The bottle-guide 25 acts as a gage to center the bottle beneath the filling-head when the finger is withdrawn due to the 40 slide moving inwardly, the bottle being retained within the bottle-guide by means for obvious reasons not shown and described in this application.

The guide also serves as an ejector for the 45 bottle after the latter has been filled and as the finger is restored in position beneath the filling-head.

In the operation of the machine, the rotation of the table 5 causes the lugs 20, 20, to 50 pass through the slots 21, 21, in the cap-chute 19, and to rake out a single cap C for each finger. The parts at that time are in the normal relation shown in Figs. 1 and 2, in which the upper end of the sleeve 6 is 55 just a trifle below the upper end of the finger and the receiving-cup, thereby forming an annular groove or well which receives the outer flange of the cap and forms a uniform support therefor throughout the entire length and breadth of the cap flange while the center of the cap is in position over the end of the cap-finger.

The advantage of this is perfectly obvious as will be seen by referring to Fig. 3. 60 In the descent of the filling-head H, the re-

ceiving-cup 8 is first forced down by the head, whereupon the rubber throat 17, just within the mouth of the head, passes down around the upper end of the sleeve without disturbing the cap, which is being centered upon the upper end of the finger while its flange is being supported and guarded by the sleeve. It is not until the elastic ring 17 has passed down below the cap that the sleeve 6 itself is released and drops out of the way, when the cap is frictionally forced and fastened within the conical throat of the head. 70 75

After a cap has thus been placed in the throat, the filling-head lifts from the finger, 80 allowing the sleeve and receiving-cup to rise and resume their normal relative positions with respect to the finger, after which an empty bottle is moved into the place previously occupied by the finger, whereupon the head again descends over it until the elastic ring 17 shall have descended far enough to embrace the bottle-neck to make an air and water-tight joint, when the bottle is filled as explained in the accompanying application. 85 After this, the cap is clenched in place around the bead at the bottle-mouth, and the head again lifts away from the bottle, and the bottle is discharged from the machine. 90 95

Having fully described my invention, what I claim as new and desire to secure by Letters Patent, is:—

1. The combination with a cap-finger, of a sleeve and receiving-cup concentrically mounted thereon, the sleeve and cup slidably connected with each other and the sleeve slidably mounted on the finger, and means for automatically locking the sleeve and finger together. 100 105

2. The combination with a cap-finger, of a sleeve and receiving-cup concentrically mounted thereon, the sleeve and cup slidably connected with each other and the sleeve slidably mounted on the finger, and means for automatically locking the sleeve and finger together, said locking means permitting the receiving-cup to slide while precluding its turning at the same time it locks the sleeve to the cap-finger. 110 115

3. The combination with a cap-finger, sleeve, and receiving-cup, of means for automatically locking the sleeve and finger together, and for permitting the receiving-cup to slide and preventing its turning on the sleeve. 120

4. The combination with a cap-finger, sleeve and receiving-cup, of means for automatically locking the sleeve and finger, and for permitting the receiving-cup to slide while preventing its turning on the sleeve, said locking means serving to automatically lock the sleeve and finger together. 125

5. The combination with a stationary cap-finger, a sleeve and receiving-cup concentri- 130

- cally mounted thereon, and a spring sustaining the receiving-cup in its normal position, of means for automatically locking the sleeve and finger together in such relative position 5 with respect to the receiving-cup that an annular groove is formed at the top of the cap-finger in position to receive the flange of the cap resting on the sleeve with the center of the cap over the end of the finger.
- 10 6. The combination with a stationary cap-finger, a sleeve and receiving-cup concentrically mounted thereon, and a spring yieldingly sustaining the receiving-cup in its normal position, of means for automatically 15 locking the sleeve and finger together in such relative position with respect to the receiving-cup that an annular groove is formed at the top of the cap-finger which receives the flange of the cap on the sleeve 20 with the center of the cap over the end of the finger, and means for adjusting the height of the finger.
7. The combination with a cap-finger, a sleeve, and a receiving-cup, the latter two

concentrically and slidably supported by the 25 finger, and a spring bearing upwardly against the receiving-cup, of a gravity lock normally confined in an opening in the sleeve, the cup having a groove traversed by the gravity lock, and a pocket at the 30 outer end of the groove to receive the gravity lock when the sleeve is forced down to its limit, and the finger having a recess in position to register with the opening in the sleeve to receive the gravity lock when the 35 parts are in their normal position, whereby the sleeve and finger are locked together.

8. The combination with a cap-finger, of a sleeve and a receiving-cup concentrically mounted thereon, the sleeve and cup slidably connected with each other, and the sleeve slidably mounted on the finger. 40

In testimony whereof I affix my signature, in the presence of two witnesses:

SAMUEL KAYE.
